UNITED STATES PATENT OFFICE.

BRIAN C. BULLEN, OF PATERSON, NEW JERSEY.

SIGHT FOR FIREARMS.

1,198,888.

Specification of Letters Patent. Patented Sept. 19, 1916.

Application filed January 10, 1916. Serial No. 71,324.

To all whom it may concern:

Be it known that I, BRIAN C. BULLEN, a citizen of the United States, and a resident of Paterson, in the county of Passaic and State of New Jersey, have invented a new and Improved Sight for Firearms, of which the following is a full, clear, and exact description.

This invention relates to sighting devices for firearms and has for an object the provision of an improved arrangement to be used in target shooting whereby more accurate firing may be produced.

Another object in view is to provide an adjustable circular front sight so as to encircle the bull's-eye when the device is in use.

A still further object in view is to provide a sighting device at the front and rear of the firearm which may be adjusted to produce any sized opening so as to shut out all undesirable rays of light while allowing the eye to view the bull's-eye and a small space around the same.

In the accompanying drawing: Figure 1 is a plan view of an iris diaphragm; Fig. 2 is a plan view of an iris diaphragm with a base connected thereto forming certain features of the invention; Fig. 3 is a side view of a rifle and target, certain parts being shown in perspective, illustrating the use of the sights thereon.

Referring to the accompanying drawing by numerals, 1 indicates an ordinary iris diaphragm which is adapted to be soldered or otherwise rigidly secured to a standard 2, as shown in Fig. 3, which standard may be adjustable and which standard is also pivotally mounted at 3 so as to be moved out of the way or up into an operative position.

An operating arm 4 of any desired structure is provided for the diaphragm 1 whereby the opening may be increased or decreased as preferred. As shown in Fig. 2, and also on the front of the rifle shown in Fig. 3, the iris diaphragm structure 5 is provided with an arm 6 at one side for opening and closing the shutters of the diaphragm. A base 7 is rigidly secured to the diaphragm in any suitable manner so as to be fitted on to the front of the rifle barrel in correct position.

As shown in Fig. 3, a target 8 is disclosed provided with a bull's-eye 9, the arrangement being such that when a person using

the rifle looks through the iris diaphragms 1 and 5 the bull's-eye will be seen and a circle 55 of white 10 will also be seen around the bull's-eye. The iris diaphragm 1 at the rear of the rifle is used in the capacity of what is known as a peep-sight, while the iris diaphragm 5 at the front is adjusted so that a 60 person looking through the peep-sight at the rear will look through the opening at the iris diaphragm 5 and will see the bull's-eye 9 in the center of a white circle. This arrangement of sights is preferable for only 65 comparatively short distance, as for instance, from 100 yards to 800 yards. From this it will be observed that the front sight will, in a certain sense, frame the bull's-eye and the entire bull's-eye will be seen regardless of the distance. When the distance is short the iris diaphragm 5 is adjusted so that the opening therein will be of a proper size to merely disclose the bull's-eye and a slight space around the same, which is also 70 75 true when the bull's-eye is at a great distance.

In the use of ordinary bead sights at the front it is usually necessary for part of the sight to obscure part of the bull's-eye in order to correctly sight the rifle, and in doing this the bull's-eye is often obscured to such an extent as to cause the shot to be directed at some other spot. By providing an adjustable diaphragm structure having an infinite adjustment the entire bull's-eye may be observed and a slight clear space around the same which, when thus observed, insures the rifleman that his sight is correct.

What I claim is:

1. In a sight of the character described, the combination with a rifle, of a sighting member at the rear of the rifle, an iris diaphragm at the front of the rifle, said diaphragm being provided with a foundation 95 or base connected to said rifle and with an operating lever for producing any desired aperture.

2. In a device of the character described, the combination with a rifle, of an iris diaphragm front sight, and an iris diaphragm rear sight, the iris diaphragm front sight being such as to cause the bull's-eye to be encircled and framed when the rifle is in use.

3. In a sight of the character described,

a peep-sight arranged at the rear of the rifle, and an iris diaphragm arranged at the front of the rifle, said iris diaphragm being formed with a base and means for adjusting the shutters of the diaphragm whereby a person looking through the peep and through the front sight may see the

5 bull's-eye on a target and a slight open space around the bull's-eye in case the rifle is correctly aimed.

BRIAN C. BULLEN.
